MILK JUG

Hiawatha Thompson Storr, 81 Buckingham Road,
Brighton, Sussex, England

Original design application Sept. 19, 1960, Ser. No. 62,195,
now Patent No. 192,815, dated May 15, 1962. Di-
vided and this application Apr. 2, 1962, Ser. No. 69,515

Term of patent 14 years

Claims priority, application Great Britain Mar. 21, 1960

(Cl. D44—21)

Fig. 1.

Fig. 2.

FIGURE 1 is a perspective view from above and one side of a milk jug showing my new design,

FIGURE 2 is a side elevation of the same.

This application is a division of my application Serial No. D. 62,195, filed September 19, 1960, now Patent Number D. 192,815 of May 15, 1962.

I claim:

The ornamental design for a milk jug, as shown and described.
